(57) **CLAIM**

The ornamental design for a stand for a Bluetooth transmitter, as shown and described.

DESCRIPTION

FIG. 1 is a left and back perspective view of the Bluetooth transmitter showing my new design.

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

Any broken lines in the figures are for illustrative purposes only and form no part of the claimed design.
